UNITED STATES PATENT OFFICE.

WILLIAM T. CARROLL, OF WORCESTER, ASSIGNOR TO GEORGE DRAPER & SONS, OF HOPEDALE, MASSACHUSETTS.

SUPPORT FOR SPINNING-SPINDLES.

SPECIFICATION forming part of Letters Patent No. 368,069, dated August 9, 1857.

Application filed February 17, 1852. Serial No. 52,947. (No model.)

To all whom it may concern:

Be it known that I, WILLIAM T. CARROLL, of Worcester, county of Worcester, State of Massachusetts, have invented an Improvement in Supports for Spinning-Spindles, of which the following description, in connection with the accompanying drawing, is a specification.

My invention relates to that class of spindles which are adapted to move laterally at the lower end to enable the spindle to find its true center of rotation, and is herein shown as embodied in a spindle having a sleeve-whirl.

My invention consists in a spindle, its sleeve-

whirl, supporting-tube, and detached laterally-movable or loosely-held lower bearing, and means to restrain the rotation of the said lower lateral bearing, combined with a tipping or rocking auxiliary bolster or upper bearing

located above the whirl and means to hold the said bearing, as will be described; also, in a supporting-tube closed at its bottom to form an oil-chamber, and a detached lower bearing externally smallest at its lower end and enlarg-

ing upward toward the whirl and free at its lower end to move in the supporting-tube with the foot of the spindle as it seeks its true center of rotation, combined with means to restrain the said bearing from rotation within

the said supporting-tube, substantially as will be described; also, in the combination of a supporting-tube having a closed bottom with a loosely-held or detached bearing supported at its lower end within said tube, the bearing

tapering from its center to its ends and movable bodily throughout its length within the supporting-tube and leaving a chamber between it and the said tube for oil; also, the combination of a supporting-tube having a

closed bottom with a bearing supported therein at its lower end, the bearing tapering from its center toward its lower end, thereby permitting the bearing to oscillate within the said tube, and leaving a chamber between it and the said tube for oil, and means for positively restraining the bearing from turning.

By the employment of the auxiliary bolster or upper bearing above the whirl, the spindle when it is deflected or tipped from its vertical position will come in contact with the bol-

ster or upper bearing, and its further deflection will be stopped.

In practice the internal diameter of the auxiliary bolster or upper bearing will be a little larger than the diameter of that part of the 55 spindle within it, so that the spindle when running in perfect or absolutely central position will rotate within and not touch the interior of the said auxiliary bolster or upper bearing.

The auxiliary bolster or upper bearing is shown as adapted to tip or rock in its supporting-shell, that being the approved plan to secure the most perfect alignment of the bolster with the spindle.

The supporting-tube for the lower bearing being closed at its bottom enables the formation of a chamber to contain oil, and also permits the said bearing to be dropped loosely into the said chamber and be interposed between the spindle and the said tube, where it is free to move laterally or tip or rock in presence of the oil in the said chamber.

I have dispensed with all fibrous packing between the lower bearing and its surrounding supporting-tube, and to keep the said bearing from rotating, but yet permit it to move in the said supporting-tube as the lower end of the spindle moves to find its true center of rotation, I have employed a pin-and-slot connection between the said tube and bearing.

The drawing shows in vertical section the principal part of a spindle, its whirl, its auxiliary bolster or upper bearing, and the shell within which it is placed, together with the 85 lower bearing and supporting-tube and their connection, they being combined and arranged to illustrate my invention.

The supporting-tube *a*, held in suitable manner in the rail *a'*, receives within it a detached 90 lower bearing, *b*, shown as open at its lower end to permit the pintle *c'* of the spindle *c* to pass through it and rest on the foot-step 2, forming part of the said supporting-tube. This detached bearing *b* is so shaped externally that 95 it may move within the tube *a*, in which it is placed loosely, and, as herein shown, its outer portion is of greater diameter near its center than at its ends.

The bearing *b* is prevented from rotating in 100

the tube *a* by means of a pin, *c*, connected with the tube *a* and extended into a slot in the said bearing.

The bearing *b* is described as detached, or, 5 in other words, it is not immovably fixed with relation to or in the tube *a*, but has just enough play therein to permit the bearing to move sufficiently by the action of the spindle within it to compensate for and neutralize the jar due 10 to the rapid rotation of the spindle when unevenly loaded; but in no event can the bearing *b* rotate freely within the tube or well with the spindle, for the said bearing has co-operating with it a pin or projection which 15 strains its rotation with the spindle.

The sleeve-whirl *d d'*, which may be of any usual construction, is extended down over and about and so as to inclose the tube *a*.

I have found that a spindle of the kind described may be materially improved as to its action by combining with it above the whirl an auxiliary bolster or upper bearing, *e*, it being preferably of such internal diameter with relation to the diameter of the spindle within it that when the spindle is running perfectly true it will not touch the said auxiliary bolster or upper bearing; but as soon as the spindle from any cause is deflected from true perpendicular position it will strike against the said auxiliary bolster or upper lateral bearing, and its tipping movement will be immediately checked and counteracted. This auxiliary bolster or upper bearing will be supported in an outer shell, *f*, held in an upper rail, *g*, and 25 the shape of the auxiliary bolster or upper bearing externally and its support within the said shell, as shown, is such that the said auxiliary bolster or upper bearing may rock to a limited extent upon that portion of its 30 perimeter which fits the shell.

I am aware that a spindle-bearing has been placed in a supporting-tube in connection with an independent step, the said bearing being surrounded by an elastic or fibrous packing, 45 and such I do not claim; but in this my invention the bearing *b*, placed loosely in the tube *a*, is free to move with the spindle as its foot moves laterally to find its true center of rotation, yet the said bearing moving in the chamber of the tube *a* is positively restrained from 50 rotation with the spindle by reason of the slot-and-pin connection shown, the size of the pin and slot being such as not to interfere with the rocking and tipping movement of the lower bearing, *b*, as the foot of the spindle moves or shakes.

I am aware that United States Patent No. 153,991 describes that a step-socket shown therein is made with a cylindrical bore or 55 chamber of a definite depth, and that a bushing made of a smaller diameter than the bore excepting at one part, which is made larger and of a spherical form and of a diameter to accurately fit the cylindrical bore of the socket, 60 is inserted in the said socket, the bottom of the bushing resting upon the bottom of the bore of the socket; but in such a contrivance

the bushing cannot move bodily in a lateral direction throughout its length as in this my invention.

I claim—

1. The spindle, its whirl, the supporting-tube, and the movable bearing within it, combined with a loosely-held auxiliary bolster located above the sleeve-whirl, and with the 75 bolster-rail and means to hold the said auxiliary bolster, substantially as and for the purposes set forth.

2. The spindle, its whirl, a supporting tube, and a loosely-held or detached bearing made 80 laterally movable bodily throughout its length, combined with an auxiliary bolster or upper bearing located above the said whirl, and with means to hold the said bolster, substantially as described.

3. The spindle provided with a whirl, a supporting-tube, a detached lower lateral bearing therein, and means to restrain the said bearing from rotation with the spindle, combined with a loosely-held auxiliary bolster or 90 upper lateral bearing, and with means to hold or support the said bolster above the whirl, substantially as described.

4. The spindle provided with a whirl, a supporting-tube, a detached bearing made laterally movable therein throughout its entire length, and means to restrain the said bearing from rotation with the spindle, combined with an upper auxiliary bolster, and with means to hold or support the said bolster above the 100 whirl, substantially as described.

5. A supporting-tube closed at the bottom to form an oil-chamber, a detached lower bearing enlarging from its lower end upward toward the whirl and free at its lower end to 105 move in the supporting-tube with the foot of the spindle as it seeks its true center of rotation, combined with means to restrain the said bearing from rotation within the said supporting-tube, substantially as described. 110

6. The combination of a supporting-tube having a closed bottom with a loosely-held or detached bearing supported at its lower end within said tube, the bearing tapering from its center to its ends and movable bodily 115 throughout its length within the supporting-tube, and having a chamber within the said tube for oil, substantially as described.

7. The combination of a supporting-tube having a closed bottom, with a bearing supported therein at its lower end, the bearing tapering from its center toward its lower end, thereby permitting the bearing to oscillate within the said tube, and leaving a chamber 120 between it and the said tube for oil, and means 125 for positively restraining the bearing from turning, substantially as described.

In testimony whereof I have signed my name to this specification in the presence of two subscribing witnesses.

WILLIAM T. CARROLL.
